UNITED STATES PATENT OFFICE.

CARL WEISSE, OF ALtenburg, GERMANY.

TILL.

No. 853,430.

Specification of Letters Patent.

Patented May 14, 1907.

Application filed January 24, 1907. Serial No. 353,894.

To all whom it may concern:

Be it known that I, CARL WEISSE, a citizen of the German Empire, and a resident of Altenburg, Germany, have invented new and 5 useful Improvements in Tills, of which the following is a specification.

The object of the present invention relates to an improved till with an alarm, which operates, upon said till being opened by any un- 10 authorized person.

In the accompanying drawing:—Figure 1 is a longitudinal section of the till in its disengaged position. Fig. 2 is a plan. Fig. 3 is a longitudinal section with the alarm de- 15 vice engaged, and Figs. 4 and 5, are a modification.

The till consists of the box *a* in the interior of which a movable frame *b* slides, which carries a number of keys *d* provided with fingers 20 *k*. The keys *d* are covered by a finger-plate *c*. Below said keys, pawls *e* are arranged in a number equal to the number of the keys, and rotatable around their pivots. These 25 pawls *e* rest on a movable plate *f*, which is provided with a bar *i*, said bar having abutments *g* and *h*, the abutment *g* corresponding with a spring influenced abutment *m*. *l* represents the alarm bell. Now, upon preventing the till being opened, one or more 30 pawls *e* are to be turned upward at an angle of 180°, and then the drawer of the till is to be closed. Upon any attempt to open the drawer again, the fingers *k* of the keys *d* push against the pawls *e*, whereupon the plate *f* and bar *i* become displaced, that is to say, said 35 plate and bar are drawn outward just as much as the slots *h'* provided in the bar *i* may allow. By this movement of the bar and plate, the abutment *g* becomes disengaged

with the spring influenced abutment *m* and 40 situates itself against *g*, thus preventing the drawer being pushed back again. Simulta- 45 neously with the displacement of the abutment *m*, the abutment *h* is influenced which operates a lever of the bell *l* whereupon the latter rings. The abutment *h* may also be situated outside the till, as shown in Fig. 4. It is then necessary that the drawer slides in grooves. The bell may be attached to the 50 table top and is similarly operated upon pull- 55 ing out the drawer. The attempts to open the till can also be indicated by means of an adjustable double base, or by means of the side walls, or by means of both the double base and the side walls simultaneously, as shown in Fig. 5. Of course these parts must be in suitable connection with the alarm device.

Having fully described my invention, what I claim and desire to secure by Letters Patent is:

A till, comprising in combination, keys (*d*) and adjustable pawls (*e*) in which the at- 60 taching plate for the pawls is provided with a slide bar, or the base of the drawer in connec- 65 tion with the attaching plate, or any other part of said drawer, or the whole drawer can be displaced upon the attempt of opening the drawer by any unauthorized person, thus locking the drawer and simultaneously oper- 70 ating a bell, substantially as described and shown and for the purpose set forth.

In testimony whereof I have hereunto set my hand in the presence of two subscribing witnesses.

CARL WEISSE.
